UNITED STATES PATENT OFFICE.

EDWARD O. TINSLEY, OF BROOKLYN, NEW YORK, ASSIGNOR TO ROBERT GAIR COMPANY, OF BROOKLYN, NEW YORK, A CORPORATION OF NEW YORK.

KNOCKDOWN DISPLAY-CONTAINER.

1,234,421.

Specification of Letters Patent. Patented July 24, 1917.

Application filed July 13, 1916. Serial No. 108,997.

To all whom it may concern:

Be it known that I, EDWARD O. TINSLEY, a citizen of the United States, residing in Brooklyn, in the county of Kings and State 5 of New York, have invented certain new and useful Improvements in Knockdown Display-Containers, of which the following is a specification.

This invention relates generally to collapsible boxes, and more especially to knock-down boxes that may be flattened out for the purpose of shipping a quantity of such boxes empty, and that may be practically instantly assembled for use as a container.

15 The present invention contemplates the provision of a knock-down box made of foldable material, such as paper board and the like, which may be flattened out for the purpose of shipping a quantity of the boxes 20 empty, which, on the other hand, may be quickly assembled for use as a container for shipping articles and which may be furthermore so assembled as to afford an advantageous display container for advertising 25 purposes and the like.

The invention further contemplates the provision of a container especially adapted to display advertising matter, to which end, among others, the container is provided with 30 means for conveniently and advantageously carrying advertising matter, and with means for conveniently and advantageously positioning the container to display its advertising matter.

35 These and other features, capabilities and advantages of the invention will appear from the subjoined detail description of specific embodiment thereof illustrated in the accompanying drawings, in which—

40 Figure 1 is a plan of the preferred form of knock-down container flattened out ready for shipment.

Fig. 2 is a perspective of the container assembled for use and closed.

45 Fig. 3 is a perspective of the container assembled for the purpose of display, showing in dotted lines the combined auxiliary cover and base support, in its intermediate position being shifted from cover to base-position or vice-versa.

Figs. 4 and 5 are plan views of blanks before they are secured together to form the flattened out container illustrated in Fig. 1.

Fig. 6 is a section on the line 6—6 of Fig. 2.

55

Fig. 7 is a fragmental section on the line 7—7 of Fig. 2.

Fig. 8 is a plan view showing the knock-down container partially assembled.

Fig. 9 is a plan of a one-piece blank from 60 which the container may be composed, instead of the two blanks illustrated in Figs. 4 and 5, respectively.

In the embodiment illustrated in Figs. 1 to 8 inclusive, a knock-down container is 65 formed from the two blanks A and B, illustrated in Figs. 4 and 5 respectively. The blank A comprises the enlarged rectangular portion 10 and the elongated strip 11 extending at right angles therefrom. The portion 10 is preferably provided with the six 70 scorings or indented folding lines 12, 13, 14, 15, 16, and 17, running parallel with one another and parallel with the upper and lower edges 18 and 19 respectively of the 75 portion 11. The scorings 12 and 13 are continuations of the edges 18 and 19 respectively. The scoring 12 defines the display board support 20 formed between such scoring 12 and the adjacent parallel edge 21 of 80 the portion 20 of 10.

The portion 11 is defined from the portion 10 by the scoring 22, which is in alinement with the elongated edge 23 of the portion 10, which edge 23 is parallel to the edge 24 on 85 the other side of the portion 10 and perpendicular to the scorings 12 to 17 inclusive. The portion 11 is provided with the scorings 25, 26 and 27, all parallel to the scoring 22. The scoring 27 defines the anchoring flange 90 28 formed between the extreme edge 29 of the portion 11 and the scoring 27. The distance between the scorings 25 and 26 is equal to the distance between the scoring 22 and the edge 24 of the portion 10, thereby forming 95 the two main longitudinal walls C and D of the collapsible box to be produced when the blanks are assembled for the purpose; and the distance between the scorings 22 and 25 is equal to the distance between 100 the scorings 26 and 27, thereby forming the two main end walls E and F of the collapsible box to be produced. The wall portion D is preferably provided with a recess 30 receding from the edge 18, which recess 30, 105 when the box is assembled, will appear at the

upper front edge of the same where the user's finger may conveniently be inserted for withdrawing or raising the cover that may be anchored by said wall member D in 5 the manner hereafter to be described.

The distance between the scorings 13 and 15 is equal to the distance between scorings 12 and 13, and the distance between the scorings 15 and 17 is equal to the length of the 10 wall members E and F. Similarly, the distance between the scorings 14 and 16 is equal to the length of the wall members E and F. The reason for the just recited dimensions is 15 as follows: When the collapsible box is assembled and closed, the portion between the scorings 15 and 17 will serve as the cover member H, the portion between the scorings 13 and 15 will rest up against the wall member C, and the portion between the scoring 20 17 and the adjacent parallel edge 31 of the portion 10 will serve as an anchoring flap to be disposed adjacent to the wall member D. The blank B comprises the main rectangular portion 32 and the two flanges 33 25 and 34 extending laterally from the portion 32. The flange 33 is defined from the portion 32 by the scoring 35 in alinement with the elongated edge 36 of the portion 32. The flange 34 is defined from the portion 32 by 30 the scoring 37 in alinement with the elongated edge 38 of the portion 32, which edge 38 is parallel to the edge 36. The portion 32 is provided with the scorings 39, 40 and 41 parallel with one another and perpendicular to the edges 36 and 38. The 35 scorings 40 and 41 are in alinement with the end edges of the flanges 33 and 34, and with the scorings 35 and 37 define the floor member K of the box to be produced. The scoring 41 defines the flange 42 formed 40 between the adjacent parallel edge 43 of the portion 32 and the scoring 41. The distance between the scorings 39 and 40 is preferably equal to the distance between the 45 scoring 41 and edge 43, and forms the anchoring portion 45, and the width of each of the flanges 33 and 34 is also preferably equal to the distance between the scorings 39 and 40. The portion formed between the 50 scoring 39 and the adjacent parallel free edge 44 of the portion 32 is preferably extensive in area and forms the display board G of the box when assembled for display. When securing the blanks A and B to one 55 another to produce the flattened out collapsible box illustrated in Fig. 1, the blank A is preferably folded along the scorings 22, 25, 26, and 27, and at least along two of the scorings spaced from one another by 60 one of the remaining scorings so that the anchoring flange 28 may be brought over into contact and be disposed to rest on the wall member C, thereupon the anchoring portion 45 is secured to the wall member C 65 with the flange 28 between the same, as illus-

trated in Figs. 7 and 8, either by some suitable adhesive substance or staples, the present illustration contemplating an adhesive substance for the purpose. When the portion 45 is so secured to the wall member C, the scorings 39 and 40 will substantially register with the scorings 12 and 13, respectively. When the blank A is so secured to the blank B and folded along the scorings 25 and 27, in flattened out position, 70 it will assume the appearance illustrated in Fig. 1.

When it is desired to assemble the attached blanks A and B, illustrated in Fig. 1, to produce a closed container, such as 80 illustrated in Fig. 2, the blank A will be further folded along the scorings 22 and 26, to assume a rectangular inclosure, then the blank B folded along the scorings 35, 37, 40, and 41, the flanges 33, 34, and 42 inserted inside of the thusly formed inclosure, so that the flanges 33, 42 and 34 will be disposed adjacent to the wall members F, D, and E, respectively, whereby a container will be formed having the portion K as a 90 floor member and the wall members C, F, D, and E registering with the portions 45, 33, 42, and 34, respectively as double wall members. Then the blank B will be folded along the scoring 39 so that the display 95 board G will fold over to cover the container and the blank A folded along the scorings 12, 13, 15, and 17, whereupon the portion between the scorings 13 and 15 will be folded over to rest against the wall member C, the display board support 20 folded down on the display board G, and the cover H folded over both the display board support 20 and the cover G and the flange formed between the scoring 17 and edge 31 100 inserted between the wall member D and the flange portion 42. When the blanks A and B are folded and assembled as aforesaid they will assume the appearance illustrated in Fig. 2. When it is desired to assemble the attached blanks A and B to produce the display container illustrated in Fig. 3, the blanks A and B will be folded 105 in the same manner as required for producing the container formed by the floor member K and the double wall members composed of the wall members C, F, D, and E, registering with the portions 45, 33, 42, and 34, respectively; but the display board G and display board support 20 will not be 110 folded over to cover the container thus formed, and the blank A not folded along the scoring 13 but folded along the scorings 15 and 17, and the flange formed between the scoring 17 and edge 31 inserted upward 115 between the wall member D and flange 42 and it will be seen that the angle of tilt of the box-portion holding the goods displayed, may be varied, accordingly, as the flange between 17 and 31, is passed further into 120 125 130

the box-portion, or vice-versa. When the blanks A and B are folded and assembled in the manner just described, they will assume the appearance illustrated in Fig. 3.

5 Should it be desired to support the container for display purposes, at a different angle than that illustrated in Fig. 3, this may be accomplished in various ways. One way is illustrated, and that is by folding the 10 blank A along the scorings 14 and 16 instead of along the scorings 15 and 17, and then inserting the flange formed between the scoring 16 and the edge 31 up between the wall member D and the flange 42. In 15 this condition the portion formed between the scorings 14 and 16 will be disposed on the supporting table or the like.

In the embodiment shown in Fig. 9, the one-piece blank is illustrated, which comprises essentially two portions A' and B' substantially identical with the blanks A and B of the embodiment illustrated in Figs. 1 to 8 inclusive. Practically the only difference between the two embodiments is that 25 instead of providing an anchoring flange 28, such as illustrated in Fig. 4, the wall member F' of the embodiment illustrated in Fig. 9 which corresponds to the wall member F of the blank A of Fig. 4, is integral 30 with a lateral extension of the portion 45' of the embodiment illustrated in Fig. 9, which corresponds to the portion 45 of the blank B of Fig. 5. In the embodiment illustrated in Fig. 9 the portion 45' is secured 35 to the wall member C', similar to the manner in which the portion 45 is secured to the wall member C of the embodiment illustrated in Figs. 1 to 8. The remaining portions of the embodiment illustrated in Fig. 9 40 are substantially identical with corresponding portions of the embodiment illustrated in Figs. 1 to 8 inclusive, and therefore without describing the embodiment illustrated in Fig. 9 in detail, the various parts therein 45 corresponding to parts of the embodiment illustrated in Figs. 1 to 8 inclusive, are designated with corresponding reference characters that have the prime exponents, thus where a portion of Figs. 1 to 8 inclusive 50 would bear the reference character D, a corresponding portion of Fig. 9 would bear the reference character D'.

It is obvious that various changes and modifications may be made to the details of 55 construction without departing from the general spirit of the invention.

I claim:

1. A collapsible box composed of foldable material, comprising two main-portion secured to one another; a three walled portion secured to one of the main-portion and forming with a part of such main-portion a four walled inclosure; a floor-member on one of said main-portion; flanges secured 60 to said floor-member and coöperating with

said inclosure to anchor the floor-member in place adjacent to said inclosure; an inner cover on one main portion and a cover-member on the other of said main-portion, adapted to be folded over the inclosure in 70 one position to form an auxiliary outer cover, and when folded in the other position, forming an inclined supporting base-portion for display purposes.

2. A collapsible box composed of foldable 75 material, comprising two main-portion secured to one another; a three walled portion secured to one of the main-portion and forming with a part of such main-portion a four walled inclosure; a floor-member on 80 one of said main-portion; flanges secured to said floor-member and coöperating with said inclosure to anchor the floor-member in place adjacent to said inclosure; a cover-member on the other of said main-portion; 85 and a flange on said cover-member coöperating with the inclosure and one of the flanges of said floor-member to anchor said cover-member in box forming position, and when in the reverse position in combination 90 with the cover portion forming an inclined base-support.

3. A collapsible box composed of foldable material, comprising two main-portion secured to one another; a three walled portion 95 secured to one of the main-portion and forming with a part of such main-portion a four walled inclosure; a floor-member on the inner of said main-portion; flanges secured to said floor-member and coöperating 100 with said inclosure to anchor the floor-member in place adjacent to said inclosure; and a cover and display board on one of said main-portion extending upward from the box formed by the inclosure and floor member. 105

4. A collapsible box composed of foldable material, comprising two main portions secured to one another, a three walled portion secured to one of the main-portion and forming with a part of such main portion a four walled inclosure; a floor-member on one of said main portions; flanges secured to said floor-member and coöperating with said inclosure to anchor the floor-member in 110 place adjacent to said inclosure; a combined cover and display-board on one of said main-portion extending upward from the box formed by the inclosure and floor-member; and an auxiliary cover on the other of said 115 main-portion adapted to be folded over and anchor the display board over the inclosure when it is desired to close the box formed by the inclosure and floor-member, and when folded in the reverse direction to form an inclined base-support for display purposes. 120

5. A collapsible box composed of foldable material, comprising two main-portion secured to one another; a three walled portion secured to one of the main-portion and 125

forming with a part of such main-portion a four walled inclosure; a floor-member on one of said main-portions; flanges secured to said floor-member and coöperating with 5 said inclosure to anchor the floor-member in place adjacent to said inclosure; a combined cover and display-board on one of said main-portions extending upward from the box formed by the inclosure and floor- 10 member; a combined auxiliary cover-member and base-support on the other of said main-portions, and a flange on said auxiliary cover-member coöperating with the inclosure and one of the flanges of said floor- 15 member either to anchor said auxiliary cover member in box closing position, or when in the reverse position in combination with the cover portion forming an inclined base support for purposes of display, sup- 20 porting the box in the display position.

6. A collapsible box composed of foldable material, comprising two main-portions secured to one another, a three walled portion secured to one of the main-portions and 25 forming with a part of such main portion a four walled inclosure; a floor-member on one of said main-portions; flanges secured to said floor member and coöperating with said inclosure to anchor the floor-member in 30 place adjacent to said inclosure; a combined cover and display board on one of said main-portions extending upward from the box formed by the inclosure and floor-member; and a combined shiftable auxiliary cover 35 and supporting member on the other of said main-portions foldably secured thereto so that it may be swung into opposite position either to support the box in display position, or into position for closing and cover- 40 ing the box.

7. A collapsible box composed of sheet material adapted to be folded into a substantially rectangular box having a shiftable combined box supporting base and 45 cover, the shiftable base and cover being foldable, and secured to the member forming the rectangular box, and adapted to be folded over in one direction, to close the rectangular box, and when folded in the other, 50 forming a base for supporting the box in an inclined display position, such combined base and cover having formed integral therewith an end flange or member for securing the same in either the covering or the sup- 55 porting position.

8. A device composed of foldable sheet material and comprising an upwardly opening box-like part; a base member foldably secured to said box-like part; and a support- 60 ing means having adjustable connection with and adjustable toward and away from the box-like part and adjustably connecting the base member thereto and adapted to support the box in different positions of adjust- 65 ment.

9. A device composed of foldable sheet material and comprising an upwardly opening box-like part; a base member foldably secured to said box-like part; and a supporting means having adjustable connection 70 with and adjustable toward and away from the box-like part and adjustably connecting the base member thereto and adapted to support the box in different positions of adjustment, said base member being provided with 75 a scoring to facilitate the folding of the same over the box-like part to close the same.

10. A box composed of foldable sheet material and comprising a box-like part provided with a pocket in its front wall; and a base member foldably secured to the rear wall of the box and provided with a fold forming an upright portion substantially the same depth as the rear wall and with a 85 flange adapted to be adjustably received in said pocket either from above or below.

11. A box composed of foldable sheet material and comprising a box-like part provided with a flange receiving pocket in its 90 front wall; and a combined base and cover member foldably secured to the rear wall of said box-like part and formed with a fold forming an upright portion and a base provided with a flange adapted to engage in 95 said pocket either from above or below.

12. In combination, a box-like part open at the top and provided in its front wall with a flange receiving pocket open at the top and bottom; a lid foldably connected 100 to the upper edge of the rear wall of the box and forming a display board; a display board support secured to said rear wall behind said display board; and a combined base and cover member foldably secured to 105 the lower edge of said rear wall and provided with a fold forming an upright portion, having substantially the same depth as said rear wall; and a base provided at its front edge with a flange adapted to engage 110 in said bracket either from above or below.

13. A collapsible box comprising two main portions secured to one another; one of the main-portions comprising a box-forming portion having a display board extending upward therefrom; the other main portion comprising a display-board supporting portion extending upward in the rear of the display board and a foldable combined cover and base support member; and means 115 on said foldable cover and base-support member for adjustably anchoring the same to the box in supporting position at one time, and to form a cover over said box to close the same at another time. 125

14. A collapsible box comprising two main-portions secured to one another, one of the main-portions comprising a floor-member, having anchoring flanges on three sides and a like flange on the fourth side in 130

central or axial alinement with a three wall-member extending from the end of said fourth flange; a wall-member anchoring flange at the free end of said flanged wall-member; the other main-portion comprising an anchoring portion adapted to be secured to the fourth flange of said first main-portion; and an interchangeable reversible member, the wall member anchoring flange being secured between such anchoring portion and the fourth flange of the first main-portion and the interchangeable reversible member being adapted at one time to form a base supporting-member for the collapsible box, and at another time to form the cover for the same.

15. A collapsible box comprising two main portions secured to one another, one of the main-ports comprising a floor-member, having anchoring flanges on three sides and a like flange on the fourth side in central axial alinement with a three wall-member extending from the end of said fourth flange; a wall-member anchoring flange at the free end of said flange wall-member, the other main-portion comprising an anchoring portion adapted to be secured to the fourth-flange of said first main portion, and an interchangeable member, the wall member anchoring flange being secured between such anchoring portion and the fourth flange of said first main-portion, the floor member anchoring flanges coöperating with said three wall member to anchor the floor-member in positich; and an inter-

changeable reversible member anchoring-flange on said interchangeable member adapted to be secured between one of the floor-member anchoring flanges and one of the wall members, at one time to anchor the 40 interchangeable reversible member in box supporting position and at another time to anchor the same in box-closing position.

16. A collapsible box comprising two main-ports secured to one another, one 45 of the main-ports comprising a floor member, having anchoring-flanges on three sides of the same and a like flange on the fourth side in central axial alinement with a three wall-member extending from the 50 end of said fourth-flange, a wall-member the other main portion comprising an anchoring-portion adapted to be secured to the fourth flange of said first main-portion; and an interchangeable reversible member, the 55 wall-member anchoring flange being secured between such anchoring portion and the fourth flange, the floor member anchoring flanges coöperating with said three wall member to anchor the floor-member in position; and the interchangeable reversible member being foldable at one point to adjustably support for display purposes at any desired tilt, the same point in a reverse direction to close and cover the box.
